UNITED STATES PATENT OFFICE

ROY V. CREEERY, OF GERMAN TOWNSHIP, ST. JOSEPH COUNTY, INDIANA

KEY RETAINER

Application filed April 22, 1931. Serial No. 531,989.

The invention relates to key retainers, and has for its object to provide a device of this character for use in combination with door locks and the like which is adapted to hold a door key in the lock whereby it cannot fall out of the lock and be lost and cannot be pushed out of the lock to permit insertion of another key at the other side of the lock or to permit the lock to be picked.

5 A further object is to provide a device of this character comprising a notched plate pivotally mounted relative to the lock plate and adapted to partially close the key hole whereby the notched portion may be selectively positioned in or out of registration with the key hole of the lock.

10 A further object is to provide a device of this character comprising a retaining plate pivoted to a lock face plate and operable by means of a pivoted arm adapted to be locked in desired position relative to the face plate to hold said retaining plate against movement.

15 With the above and other objects in view, the invention resides in the combination and arrangement of parts as hereinafter set forth, shown in the drawing, described and claimed, it being understood that changes in the precise embodiment of the invention may be 20 made within the scope of what is claimed without departing from the spirit of the invention.

In the drawing:

25 Figure 1 is a view in front elevation of a door lock face plate having my device attached thereto.

30 Figure 2 is a fragmentary plan view in front elevation showing my device applied to the door lock face plate in locking position.

35 Figure 3 is a vertical sectional view taken on line 3—3 of Figure 1.

40 Figure 4 is a fragmentary vertical sectional view showing the retaining plate operating lever in released position.

45 Figure 5 is a perspective view of my retaining plate.

50 Referring to the drawing, which illustrates the preferred embodiment of the invention, the numeral 10 designates a conventional

door lock face plate having a key hole 11 and carrying a knob 12. In spaced relation below the key hole 11 an opening 13 is formed in the face plate 10, and through this opening 13 projects a stud 14 carried by a substantially fan-shaped retaining plate 15 whose upper edge is preferably curved in an arc concentric with opening 13. The upper edge of the retaining plate is provided at its center with a notch 16 of a shape conforming to the shape of the lower portion of the key hole 11 with which it is adapted to register. A ring 17 engages the face plate 10 and encircles the opening 13. An arm 18 is pivoted at 19 on the outer end of stud 14, and is provided with a cam-shaped nose 20 adapted to bear against the ring 17.

55 My device is applied to the inner door lock face plate whereby the arm 18 projects from the inner side of the door. When it is desired to lock the door from the inside the key (not shown) is actuated to set the door lock (not shown) and the plate 15 is positioned

60 with the notch 16 out of registration with the key hole whereby the lower portion of the key hole is closed by the plate, thus preventing removal of the key from the lock. The arm 18 is then depressed into engagement with the lock face plate to force the cam nose 20 against the ring 17 and to draw the stud 14 outwardly whereby the lock face plate 10 and retaining plate 15 are drawn into frictional engagement to hold the retaining plate 65 against movement relative to the face plate.

70 This cam locking means is further facilitated by the eccentric location of the pivot 19, and by the formation of the cam which is slightly notched at its lower side for engagement with the ring 17 whereby movement from locked position is resisted. When the retaining plate

75 has been so positioned the key may not be withdrawn from the lock nor pushed out of the lock from the outside to permit insertion of another key since the retaining plate holds the key head or ward against passage through the key hole. The retaining plate cannot be tampered with or moved from the outside, and forms a second lock, complementary to the door lock, which prevents the door lock 80 from being picked. It will also be seen that

95

100

the retaining plate will serve to retain the key in the lock at all times when positioned as shown in Figure 2 whether the door is locked or not, and the key cannot fall from the lock and be lost in the opening and closing of the door.

The invention having been set forth, what is claimed as new and useful is:

1. The combination with a lock face plate having a key hole and an opening spaced from said key hole, of a retaining plate positioned at the rear of said face plate and normally closing a portion of said key hole, said retaining plate having a notch therein adapted to register with said key hole, a stud fixedly carried by said retaining plate and extending through said opening, and a handle having a cam-shaped portion, said cam being pivoted to the outer side of said stud and bearing on said face plate whereby pivotal movement of said handle and cam draws said retaining plate into frictional locking engagement with said face plate.

2. The combination with a lock face plate having a key hole and an aperture spaced from said key hole, of a retaining plate positioned at the rear of said face plate and normally shiftable relative thereto, said retaining plate normally closing a portion of said key hole and having a notch therein adapted to register with said key hole, a stud fixedly carried by said retaining plate and extending through said aperture, a ring encircling said stud and bearing on said face plate, said ring having a concave inner periphery, a handle having a rounded nose fitting into the concavity of said ring, the nose of said handle being eccentrically pivoted to the outer end of said stud whereby pivoting of said nose relative to said stud by said handle draws said retaining plate into frictional locking engagement with said face plate.

In testimony whereof I affix my signature.
ROY V. CREEERY.
